UNITED STATES PATENT OFFICE.

WALTER S. HARRISON, OF BELLEFONTAINE, OHIO, ASSIGNOR OF ONE-THIRD
TO EMERSON V. MOORE, OF SIDNEY, OHIO.

ENVELOP.

SPECIFICATION forming part of Letters Patent No. 714,179, dated November 25, 1902.

Application filed March 17, 1902. Serial No. 98,576. (No model.)

To all whom it may concern:

Be it known that I, WALTER S. HARRISON, a citizen of the United States, residing at Bellefontaine, in the county of Logan and State 5 of Ohio, have invented certain new and useful Improvements in Envelops, of which the following is a specification.

My invention relates to envelops made of paper or other suitable material and is for 10 use with various classes of mail-matter, but more particularly that class of mail-matter known as "first-class" or "letter" mail.

In the ordinary construction of envelop now in use it is a simple matter for evilly-dis- 15 posed persons to open the sealed flap by the process known as "steaming" and other methods, remove the contents of the envelop, read or retain the contents, reseal the envelop, and forward it to the addressee.

20 The object of my invention is to prevent opening and resealing envelops by so forming them that the envelop would be broken or injured, and thus show that it had been tampered with.

25 The advantages of my envelop will more fully appear hereinafter and by reference to the accompanying drawings, in which—

Figure 1 is a view of the blank from which my envelop is formed; Fig. 2, a view of the 30 envelop ready for use; Fig. 3, a view illustrating the first step in sealing my envelop; Fig. 4, the next step; and Fig. 5 the final step, or the envelop sealed ready for transmission through the mails.

35 Referring to the drawings, in which similar reference characters indicate corresponding parts throughout the several views, A represents the front or address portion of the envelop; B B, the side flaps that are first folded 40 over in forming the envelop; C, the lower flap, having the extended tongue D and the slit E. The outer edge of the flap C and the base of the tongue D are provided with mucilage or other suitable adhesive substance F

45 to join the side flaps B B and the lower flap C in forming the bag portion of the envelop.

G represents the upper or closing flap of the envelop, having a slit H therein, and is

provided with the usual mucilage or other adhesive substance I at its edge.

In sealing the envelop the mucilage I is moistened, the tongue D inserted through the slit H in the upper flap G from below, and the flap sealed, as is ordinarily done. This is the first step in the operation, as illustrated 50 in Fig. 3. The mucilage J on the body of the tongue D and K on its tip are then moistened and the tongue D turned downward, as shown in Fig. 4, the end of the tongue inserted in the slit E in the flap C, the tongue D and 55 lower part of the flap C under the slit E subjected to pressure, so as to cause the mucilage J and K to adhere, and the envelop sealed, as shown in Fig. 5.

It will be readily seen that to attempt to 60 open the envelop surreptitiously by steaming or other means would result either in breaking the tongue D or so defacing it and the envelop as to indicate that the envelop had been tampered with, and thus prevent to a 65 great extent pilfering of the contents of first-class matter.

Having thus described my invention, what I claim is—

1. An envelop consisting of an open- 75 mouthed bag and a flap to cover the mouth of said bag, a tongue integral with said bag adapted to be inserted upward through a single slit in said flap then folded down and inserted in a slit in the bag and suitably secured in sealing the envelop, substantially as shown and described.

2. An envelop constructed with a slit in the upper and lower flaps, and a tongue integral with the lower flap, the lower flap being 80 secured to the side flaps to form an open-mouthed bag, said tongue being inserted through the slit in the upper flap and then through the slit in the lower flap when sealing the envelop, substantially as shown and 85 described.

3. An envelop constructed with side flaps, a lower flap having a slit therein and an extended tongue, the edge of said lower flap and base of the tongue provided with an ad- 90hesive material for securing it to said side 95

flaps, the upper flap provided with a slit through which the tongue is first inserted in sealing the envelop, the body portion of said tongue provided with adhesive material to 5 secure it to the back of the envelop, the tip of the tongue inserted through the slit in the lower flap and provided with adhesive material on the side next the flap to secure it

therein, substantially as shown and described.

In testimony whereof I hereto affix my signature in the presence of two witnesses.

WALTER S. HARRISON.
